Frank H. Howard,

By Frank H. Howard.

UNITED STATES PATENT OFFICE.

FRANK. H. HOWARD, OF IRVINGTON, NEW JERSEY.

NECKTIE-FASTENER.

SPECIFICATION forming part of Letters Patent No. 447,826, dated March 3, 1891.

Application filed June 25, 1890. Serial No. 356,617. (No model.)

To all whom it may concern:

Be it known that I, FRANK. H. HOWARD, a citizen of the United States, residing at Irvington, in the county of Essex and State of New Jersey, have invented certain new and useful Improvements in Scarf-Holding Pins; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of this invention is to reduce the cost of neckscarfs by facilitating the operation of adjusting and securing the fastening and holding means therein and to provide a more convenient and effective holder; 20 and it consists in the improved scarf holder and fastener and in the arrangements and combinations of parts, substantially as will be hereinafter set forth, and finally embodied in the claims.

25 Referring to the accompanying drawings, in which like letters indicate corresponding parts in each of the several figures, Figure 1 is a front and Fig. 2 a side elevation of the improved holder and fastener. Fig. 3 is a section of the same, taken on line *x*, Fig. 1. Fig. 4 is a plan of a blank from which the device is formed, and Figs. 5 and 6 are respectively a rear and side elevation of the device applied to the scarf.

35 In said drawings, *a* indicates an ordinary scarf having the usual strap adapted to encircle the neck and be pinned at its free end to the body of said scarf, whereby the said scarf is fastened upon the neck, and *b* indicates the fastener and holder, made, preferably, of one piece of metal, and consisting, first, of a pin portion *c*, adapted to pass through a portion of the scarf material and project therefrom, so as to enable the said strap to 40 be caught thereon in the usual manner and fastened, the said pin thus serving as the fastener for the strap or of the scarf. The pin tapers gradually and continuously up to the point of union with concaved head, so 45 that said pin may be thrust entirely through the fabric and only the said concaved plate be exposed on the upper part of the scarf.

In connection with the pin portion is, second, a scarf-holder adapted to prevent the said scarf from riding up on the collar. This consists of a head *d*, of a concavo-convex form, and provided with curved arms *e e*, having an opening *f* between, into which the head of the usual collar-button may pass, the upper ends of the said arms being inwardly beveled, as 55 at *g g*, so as to direct the shank of said collar-button into the said opening *f* and at their upper extremities extending forward so as to bear against the back of the scarf and support the same, as will be understood. The 60 head *d* bears, as at *h*, on the said shank of the button, and thus the scarf will be prevented from riding upward. The collar-button head being larger than the opening *f*, the head is prevented from being horizontally 65 withdrawn from the button.

Prongs *k k* are or may be provided at the head of the pin or on the pin below the said head, which point in a direction opposite or away from the point of said pin, so as to prevent the pointed end of said pin from being forced out from its projecting position to a point where the scarf-strap cannot easily be fastened thereon, as will be understood. The pin is formed centrally in line with the opening *f*, and the prongs *k* are disposed on opposite sides of said central line, so as to bear evenly in holding the fastener in position.

In forming the pin I may roll the sheet metal on itself, as indicated in Fig. 1, and by 75 means of suitable dies press it down to a sharp point; but the pin may be formed and arranged, in connection with the head, in any other way, and other variations and changes may be made in the device without departing 80 from the spirit of the invention.

The fastener and holder may be readily adjusted upon the scarf and be detached therefrom with convenience and ease, and all need of sewing or of extraneous fasteners is 85 dispensed with.

Having thus described the invention, what I claim as new is—

1. The improved scarf-fastener herein described, combining with the concaved head 90 having arms *e e*, the extremities of which extend forward, as described, to engage the back of the scarf, and a central pin, substantially as described.

2. The improved scarf-fastener herein described, combining with the head having forwardly-projecting arms *e e*, with an opening between to receive the shank of the button, a
5 pin arranged in line with said opening and tapering from the point to the union with said head, substantially as set forth.
3. The improved scarf-fastener, combining therein the head having arms *e e*, a pin *c*, integral with said head, and prongs *k k* at each
10 side of the line of said pin, substantially as and for the purposes set forth.
4. The improved scarf-fastener, combining

a concaved head having forwardly-curved arms *e e*, bearing *h*, opening *f*, and inclines *g g*, and a pin *c*, formed in line with said opening and consisting of rolled metal integral with the head, substantially as set forth.

In testimony that I claim the foregoing I have hereunto set my hand this 17th day of 20 June, 1890.

FRANK. H. HOWARD.
